UNITED STATES PATENT OFFICE.

ELMER RYDER, OF ELGIN, ILLINOIS.

MOTOR-VEHICLE HEATER.

Application filed March 26, 1926. Serial No. 97,546.

One object of my invention is to provide a heater which may be readily and conveniently applied to the exhaust pipe of a motor vehicle for delivering heated air into the body of the car at a plurality of places, as for instance in advance of the front and rear seat, respectively, without employing more than one heater for each car, thereby reducing the cost of the heater equipment per car, yet obtaining as much if not more heat than with two heaters as would be required for a similar installation using heaters as heretofore made.

Another object of my invention is to provide a heater assembly by which drafts or currents of heated air are blown or forced into the car, thereby obtaining a large volume of heated air for the car.

A further object of my invention is to provide baffle means in the heater casing for increasing the length of travel of the air therethrough and thus sufficiently heat the air for car warming purposes without requiring that the heater be of undue dimensions.

A still further object of my invention is to provide a heater assembly simple, yet efficient in its construction, and which may be applied to an exhaust pipe without cutting the latter in two, thereby facilitating the application of the heater to the pipe.

Another object of my invention is to provide a construction which may fit exhaust pipes of different diameters as found in different makes of cars, thereby enabling the heater proper to be of one size for all pipes.

The invention consists further in the matters hereinafter described and claimed.

In the accompanying drawings—

Fig. 1 is a view showing the application of my heater to a car;

Fig. 2 is a longitudinal sectional view through the heater assembly applied to the exhaust pipe;

Fig. 3 is a transverse sectional view taken on line 3—3 of Fig. 2;

Fig. 4 is a sectional view taken on line 4—4 of Fig. 2;

Fig. 5 is a sectional view taken on line 5—5 of Fig. 4;

Fig. 6 is an enlarged vertical sectional view taken on line 6—6 of Fig. 1;

Fig. 7 is a fragmentary sectional view taken through the heater conduit; and

Fig. 8 illustrates a feature of construction to be hereinafter described.

In the motor car assembly shown in Fig. 1,

1 indicates the engine; 2, the exhaust pipe extending from the engine toward the rear of the car under the floor 3 thereof; and 4, 4^a indicate the front and rear seat in the body 5.

The heater assembly of my invention is applied to the exhaust pipe 2 beneath the body 5, preferably under the front seat 4, as shown in Fig. 1. The heater comprises a conduit 6, preferably U-shape and disposed to have both its legs opening into the exhaust pipe. Said conduit 6 is applied to one side of the pipe 2 and extends horizontally outward therefrom beneath the body. The legs of the conduit 6 are connected with and open through a base block 7, which fits in a rectangular opening 2^a provided in the wall of the exhaust pipe, without cutting the latter in two, as shown in Figs. 4 and 5. The block 7 has outwardly projecting lugs or ears 7^a, 7^b on the opposite sides thereof, to which are bolted bands 7^b, 7^c applied to the pipe 2 on the side opposite the block for clamping the same thereto. The conduit 6 and block 7 are preferably cast in one piece so as to cheapen the cost of construction and avoid joints through which exhaust gases may leak.

The block 7 carries a deflector, preferably in the form of a disc 8 disposed in the pipe 2 between the legs of the conduit, as shown in Fig. 5. The disc 8 has a stem 9 rotatably supported in the block 7 between the legs of the conduit, so that the disc may be turned into and out of position extending across the pipe 2 for deflecting exhaust gases from the pipe 2 into and through the conduit 6, as indicated in dotted lines in Fig. 5. For turning the disc or valve 8, the stem 9 has an arm 10 at its outer end with an actuating rod or wire 11 connected thereto.

A casing 12 encloses the conduit 6 to provide an air chamber about the same. Said casing is preferably made in upper and lower parts secured to lugs 13, 13 cast on the legs of the conduit 6 by screws 14, as shown in Fig. 4. These lugs extend outward from the conduit so as to space the casing sections therefrom. The upper and lower sections of the casing have flanges 15, 15 along their meeting edges, these flanges being secured together by screws 16, as shown in Fig. 3. The ends of the casing sections at the block 7 are turned inward to meet outwardly projecting ribs or webs 17 on the block to close the casing at the block, as shown in Fig. 4.

For supplying air to the casing 12, I provide an intake pipe 18 extending to the front of the car and having a funnel-shaped or flared inlet end 19 just behind the radiator fan 20, so that air will be blown into and through the heater casing 12, as shown in Fig. 1. This pipe 18 opens into the casing 12 adjacent the block 7 so as to deliver air at the hottest part of the conduit 6. To the opposite end of the casing 12, I attach two pipes or conduits 21, 21, one leading to the floor of the car in advance of the front seat 4, and the other to the floor of the car in advance of the rear seat 4^a, as shown in Fig. 1.

Arranged in the casing 12 are a plurality of baffle plates 22, 22. These are disposed to extend across the casing between the top and bottom walls thereof. The plates are divided into upper and lower portions cast integral with the respective sections of the casing, as shown in Fig. 4. The upper portions of the baffles abut against the lower portions of the corresponding baffles, as shown in said figure. Each baffle extends across the casing from one side and terminates short of the other side to provide an opening 23 about such end of the baffle. These openings alternate so as to increase the length of travel of the air through the casing.

The conduit 6, as shown in Fig. 7, is provided on the inside with a plurality of inwardly projecting baffles 24 to make a turbulent flow of exhaust gases through the conduit and thus turn all portions of the heated gases against the metal of the conduit to effectively heat the same.

At the place where each outlet pipe 21, 21, discharges heated air into the body of the car through the floor 3, I provide the assembly shown in detail in Fig. 6. At each of these places, I provide a pipe fitting 25 secured to the floor of the car by bolts 26, 26 and having within it a damper in the form of a disc 27 mounted on the stem 28 having an arm 29, to which is connected a pull rod 30 extending up through the floor of the car, as shown in Figs. 1 and 6. The conduit 21 is coupled to the lower end of the fitting 25, and the upper end of the latter where it opens through the floor-boards is covered by a cowl 31 held in place by the bolts 26. This cowl has its marginal portions extending downward so as to space its body portion above the open end of the fitting 25, and has a series of marginal openings 32 to permit the outflow of heated air from the assembly.

Gaskets 33, 33 are interposed between the side margins of the block 7 and the outer wall of the exhaust pipe 2, so as to provide tight joints along such parts when the block is tightly clamped against the exhaust pipe (Fig. 4). To provide joints at the opposite ends of the block 7, I provide end plates

34, 34. These are secured to the ends of the block by screws 35, and the inner edges of the plates are curved to conform to the outside curvature of the exhaust pipe 2, as shown in Fig. 8. To accommodate the 70 heater assembly to exhaust pipes of different diameters, as used in different makes of cars, I employ end plates 34 having their inner edges formed on different radii, so that there will be a set of plates to conform to the curvature of the different pipes and thus permit the heater assembly to be made standard for all sizes of exhaust pipes. 75

With my invention, only one heater is required to supply heat to two or more 80 places in the car body. This is an important factor of my invention because it reduces the cost of heater installation per car, and does the work of separate heaters, one at each place where heat is required, as with 85 heaters as heretofore made. Moreover, with my invention heated air is blown or forced into the car body, thereby giving a large volume of heated air for the car. The heater of my invention is simple in construction, is easily applied to an exhaust pipe, 90 and is efficient as a car warmer.

The structure shown and described may be variously changed and modified without departing from the spirit and scope of my 95 invention.

I claim as my invention:

1. A heater having a substantially U-shaped conduit to be attached to an exhaust of a motor vehicle, a casing enclosing said conduit and having an air intake and an outlet, baffle plates extending across the casing between the same and said conduit, said casing and plates being divided into upper and lower sections with the sections 100 of the plates cast integral with the corresponding sections of the casing, and lugs cast on the legs of the conduit to which the casing sections are attached.

2. A motor vehicle heater assembly comprising a substantially U-shaped conduit adapted to be attached to the exhaust pipe of the vehicle with both of the legs of the conduit opening into the exhaust pipe and extending laterally outward therefrom beneath the floor of the vehicle, a casing enclosing said conduit and extending to the exhaust pipe, said casing being carried by said conduit and having a cold air intake at one end and a hot air outlet at the other end, and a deflector associated with said conduit between the legs thereof and adapted to extend into the exhaust pipe for deflecting the exhaust gases into the conduit. 115

3. A motor vehicle heater assembly comprising a substantially U-shaped conduit adapted to be attached to the exhaust pipe of the vehicle with both of the legs of the conduit opening into the exhaust pipe and extending laterally outward therefrom be- 120

125

- neath the floor of the vehicle, a casing enclosing said conduit and extending to the exhaust pipe, said casing being carried by the conduit and having a cold air intake at 5 one end and a hot air outlet at the opposite end, a deflector associated with said conduit between the legs thereof and adapted to extend into the exhaust pipe for deflecting the exhaust gases into the conduit, and baffle 10 means in the casing between the same and the conduit to increase the length of travel of the air therethrough.
4. A motor vehicle heater assembly comprising a base block adapted to be clamped 15 against the exterior of the vehicle exhaust pipe over a hole in the outer wall thereof, a substantially U-shaped conduit cast integral with said block and having its legs opening therethrough into the exhaust pipe, a casing 20 enclosing said conduit and extending to and closed by said block, said casing being secured to said conduit and having a cold air intake at one end and a hot air outlet at the opposite end, a deflector carried by said block 25 between the legs of the conduit and adapted to extend into the exhaust pipe, means for clamping the block to the exhaust pipe, and interchangeable end plates for the ends of the block and having curved edges of different radii to fit exhaust pipes of different diameters.
5. A motor vehicle heater assembly comprising a base block adapted to be clamped 30 against the exterior of the vehicle exhaust pipe over a hole in the outer wall thereof, a substantially U-shaped conduit secured to said block and having both legs opening therethrough into the exhaust pipe, a casing 35 enclosing said conduit and extending to and closed by said block, said casing being secured to said conduit and having a cold air intake at one end and a hot air outlet at the opposite end, a deflector carried by said block 40 between the legs of the conduit and adapted to extend into the exhaust pipe, means for clamping the block to the exhaust pipe, and interchangeable end plates for the ends of the block and having curved edges of different 45 radii to fit exhaust pipes of different diameters.

In testimony whereof I affix my signature this 23d day of March, 1926.

ELMER RYDER.
